COAXIAL TRANSMISSION LINE FILTER
SYSTEM

Victor H. Rumsey and Percy G. Salmon, Washington, D. C., assignors to Minister of Supply in His Majesty's Government of the United Kingdom of Great Britain and Northern Ireland, London, England

Application March 19, 1946, Serial No. 655,626

6 Claims. (Cl. 178—44)

1

This invention relates to electrical frequency selective devices and in particular to frequency selective filter devices for use in a coaxial line system in which the filter device is wholly contained in the coaxial line.

In numerous applications involving a coaxial line connection between two points it is necessary to interpose a frequency selective device at some point in the system. Possible locations for the frequency selective device are at either end of the line or at some intermediate point along the line. In numerous installations it may occur that, due to space limitations, the location of such a device at either end of the line is not practical. In such a case an intermediate mounting position is required.

It is therefore an object of the present invention to provide a transmission line filter system capable of producing a maximum attenuation of one frequency band and minimum attenuation of a second frequency band.

Another object of this invention is to provide a filter device for use in a coaxial line system, said device being wholly contained in the coaxial line.

Another object of this invention is to provide a filter device for insertion in a coaxial line, said filter device providing maximum attenuation of one band of frequencies with minimum attenuation of a second frequency band.

Other and further objects and features of the present invention will become apparent upon a careful consideration of the following detailed description when taken together with the accompanying drawing, the figures of which illustrate typical embodiments of the invention and the manner in which those embodiments may be considered to operate.

In the drawing,

Fig. 1 shows in longitudinal section the typical embodiment of the features of the invention.

Fig. 2 shows, also in longitudinal section, a second embodiment of the invention.

Figs. 3 and 4 show electrical equivalents of the apparatus of Figs. 1 and 2.

Fig. 5 is a plot of attenuation versus frequency in the vicinity of the reject band of the filters of Fig. 1 and Fig. 2.

According to the general concept of the present invention, maximum attenuation of a signal of one frequency contained in a coaxial transmission line with a minimum attenuation of another frequency is achieved through the placement in one conductor thereof of two shorted

2

coaxial line sections separated by an impedance converting section of coaxial transmission line.

For optimum attenuation of energy at a particular frequency, the lengths of the shorted coaxial line sections and of the impedance converting line section are made approximately a quarter of a wave length of that frequency.

To produce optimum transmission of a different frequency signal, the characteristic impedance of the interposed impedance converting line section is made such that any complex impedance introduced by one shorted line section is cancelled by that introduced by the second shorted line section.

Also incorporated into the devices subsequently to be described in detail are certain broad banding features which widen the attenuation band and the transmission band rather than restrict them to specific frequencies, as described above.

Referring now to Fig. 1, a coaxial transmission line filter system is shown comprising an outer conductor 10 and an inner conductor 10—A having hollow ends 11 and 12. Extending into each of these ends and to a depth approximately equal to a quarter wavelength of the frequency of energy to be attenuated is an annular cavity as identified by the numerals 13, 14. Connected to the inner conductor at the bottom of each annular cavity is a conductive member possessing an enlarged central portion 15. This enlarged central portion is also approximately a quarter of a wavelength in length at the frequency to be suppressed. Support for the inner conductor assembly within the outer conductor 10 is provided by an annular ring of insulating material 16 inserted between the enlarged conductive portion 15 and the outer conductor 10.

For optimum attenuation of a particular frequency, the depth of the annular cavities 13, 14 and the length of the enlarged portion 15, are each equal to a quarter of an electrical wavelength at that frequency. Thus, cavities 13 and 14 will appear as shown in Fig. 3 as parallel resonant, highly resistive paths 17, 18 interposed serially in a first conductor 19 of an equivalent two wire transmission line. The raised portion 15 will appear as a pi-section filter 20 interposed in the first conductor 19 between elements 17, 18 and connected to the second wire 22 of the transmission line.

To produce a minimum attenuation of energy at a second, for example, lower, frequency it is desirable that the entire assembly including the annular cavities 13, 14 and the enlarged central

portion 15 present a matched impedance to the transmission line at that frequency. To fulfill this requirement, it is necessary that the impedance looking to the left direction (in Fig. 1) from the open end 11 be equal to the impedance also looking in the right direction (in Fig. 1) from the open end 11.

To fulfill this matched impedance requirement at the exemplary lower frequency, transmission of which without attenuation is desired, it is necessary that the enlarged section 15 function as an impedance converting transmission line section (24 in Fig. 4) changing the inductive impedance 23 introduced by the annular cavity 13 to the conjugate of the inductive impedance 24 introduced by the annular cavity 14. Since the length of the transmission line section 24 is fixed by the quarter wavelength requirement of the attenuation frequency, the only method of altering the impedance converting ability of section 24 is by adjusting the characteristic impedance (Z_c) of the section until the proper impedance conversion is realized. The characteristic impedance (Z_c) of the section 24 is readily calculated by the formulas:

Equation I

$$Z_c^2 + Z_c(X) \left(2 \cot \frac{2\pi L}{\lambda} \right) - R^2 - X^2 = 0$$

where:

Z_c =required characteristic impedance of line section 24

L =length of the enlarged section 15 (24)

λ =wavelength of the pass frequency

R =characteristic impedance of line comprising conductors 10 and 10A

X =reactance of each of the annular sections 13 and 14 given by jX in subsequent equation

Equation II

$$jX = jA \tan \frac{2\pi L}{\lambda}$$

where:

X =impedance of annular sections 13, 14

A =characteristic impedance of the annular coaxial sections 13, 14

L =length of the annular sections 13, 14

λ =wavelength of the pass frequency

$j = \sqrt{-1}$

It is apparent that certain compromises must be made to obtain optimum operation at both the pass and the reject frequencies. To produce optimum attenuation of a particular frequency it is desirable that (A), the characteristic impedance of the line sections 13, 14 be large because in the equation,

$$jX = jA \tan \frac{2\pi L}{\lambda}$$

a large value of (A) will produce a high impedance at the reject frequency where (L) is approximately equal to

$$\frac{\lambda}{4}$$

Such a large value of (A) is not consistent with the requirement of minimum attenuation of the pass frequency which would require small values of (A) in the same equation, for example, where (L) is appreciably less than

$$\frac{\lambda}{4}$$

at a lower frequency. A working compromise

with a value of (A) in sections 13, 14 in the range of 40-50 ohms was found to give the best results.

Thus far the discussion has been limited to conditions of attenuation of one frequency and the transmission of another frequency by the filter system. Frequently broad band action in the vicinity of one or both frequencies is required. To achieve this action, further compromises must be made in the filter design.

In one method of broad banding typically employed where a band width of 20% is required around both the pass and the reject frequencies, the resonant cavities 13, 14 were made of slightly different depths with one cavity resonating at a frequency (f_1) below the central frequency of the reject band and the other resonating at a frequency (f_2) above the central frequency. This produced a dual peak rejection characteristic as shown in Fig. 5, which is a plot of attenuation versus frequency with both coordinates increasing in the directions as shown.

The best overall rejection over a frequency band from (f_a) to (f_b) results when the rejection at frequencies (f_a), (f_b) and (f_c) is equal. Calculation of (f_c) is by equation ($f_c^2 = f_a f_b$). To achieve this effect, the frequencies (f_1, f_2) can be calculated from the following equations:

Equation III

$$f_1 = 0.854 f_a + 0.147 f_b$$

Equation IV

$$f_2 = 0.147 f_a + 0.854 f_b$$

where all symbols are as previously set forth.

This compromise upsets somewhat the matching previously obtained in the pass band because the difference in the lengths (L_1) and (L_2) of the cavities 13, 14 does not permit the employment of the simple Equation I. Equation I may still be employed, however, provided that the characteristic impedances (A_1) and (A_2) of cavities 13, 14, respectively, are selected so that

$$\left(A_1 \tan \frac{2\pi L}{\lambda} \right) \text{ equals } \left(A_2 \tan \frac{2\pi L_2}{\lambda} \right)$$

at the central frequency of the pass band and that the value of (L) as used in Equation I is the electrical length of the impedance converting line section 15. For this reason the diameter of the small left end section (Fig. 1) of the conductive member 15 is different from that of the small right end section (Fig. 1).

For optimum operation it is desirable that the "end effect" due to the separation between the end 11 of conductor 10A and the left end (in Fig. 1) of the enlarged portion 15 be small. Also, for the same reason, it is desirable that the "end effect" due to the separation of end 12 of conductor 11A and the right end (in Fig. 1) of the enlarged portion 15 be small. It is therefore desirable that these openings be no larger than is required to prevent voltage breakdown thereacross.

An alternate filter arrangement is shown in 65 longitudinal section in Fig. 2. This system is similar in many respects to the filter of Fig. 1, however, certain features such as reduced overall length are advantageous where the available length of coaxial transmission line is limited.

The filter of Fig. 2 is contained within an outer conductor 26 of a coaxial transmission line. A discontinuous inner conductor having ends 27, 28 is contained within conductor 26. Mechanical connection of the ends 27 and 28 is provided 70 by means of an axially disposed conductive rod

29 of somewhat smaller diameter. Surrounding rod 29 is a conductive cylinder 30, conductively attached to the end 27 of the inner coaxial conductor. A second, larger, conductive cylinder 31 is placed around cylinder 30. Cylinders 30 and 31 are attached, at their right ends (as shown in Fig. 2) to a short conductive cylinder 32. The connection of cylinders 30 and 31 to cylinder 32 may be made by conventional methods, as by welding or brazing.

Support of the inner conductor assembly within the outer conductor 26 is provided by means of an annular sleeve of insulating material 33 surrounding cylinder 31.

It can be seen that the filter of Fig. 2 is similar to that of Fig. 1. The cavity enclosed between the outer surface of cylinder 30 and the inner surface of cylinder 31 corresponds to the shorted annular cavity 13. Similarly the line section comprising the outer surface of cylinder 31 and the inner surface of the outer conductor 26 corresponds to the section comprising the surface of the enlarged inner conductive member 15 and the inner surface of the outer conductor 10 of Fig. 1. Also the annular cavity formed between the inner surface of cylinder 30 and the surface of rod 29 corresponds to the annular cavity 14. Therefore, the same design principles and formulae as applied to the construction of filters according to Fig. 1 are applicable to the design of the filters of the type of Fig. 2. The annular cavity formed between cylinder 30 and rod 29 is of a different length than that formed between cylinders 31 and 30 so that broad band action as described above is achieved.

It is preferable that the opening existing between the end of the outer surface of conductor 27 and the left end (as shown in Fig. 2) of cylinder 31 and also the opening between the end of conductor 28 and the cylinder 32 be small, typically no larger than is required to prevent voltage breakdown thereacross.

Typical dimensions employed in the filter shown in Fig. 1 where it was desired to permit a passage of all frequencies from 950-1150 mc. and reject all frequencies having a wavelength from 8.5 to 10.5 centimeters are as follows, with dimensions in inches:

Depth of cavity 13	0.722	50
Depth of cavity 14	0.750	
Electrical length of enlargement of member 15	0.622	
Diameter of reduced section to left of enlargement (Fig. 1) of member 15	0.146	55
Diameter of reduced section to right of enlargement (Fig. 1) of member 15	0.16	
Diameter of enlargement of member 15	0.491	
Outside diameter of ends of 10A	0.470	
Inside diameter of ends of 10A	0.3125	60
Inside diameter of conductor 10	0.875	
Length of insulating material 16	0.622	
Type of insulating material 16	poly-F	
Spacing between ends 11, 12 and enlargement 15	0.1875	65

Typical dimensions (in inches) of filter of Fig. 2 for a reject band of 10.5-12.5 centimeters and for pass action as above.

Inside diameter of outer conductor 26	0.875	70
Diameter of inner conductor 27, 28	0.375	
Diameter of rod 29	0.053	
Inside diameter of cylinder 30	0.125	
Outside diameter of cylinder 30	0.187	
Inside diameter of cylinder 31	0.4375	75

Outside diameter of cylinder 31	0.500
Length of cavity formed between cylinders 30, 31	0.900
Length of cavity formed between cylinder 5 30 and rod member 29	1.000
Length of cylinder 31	1.000
Spacing between end of 27 and left (Fig. 2) end of 31, and between end of 28 and annular ring 32	0.187

10 Type of insulating material 33 poly-F

From the foregoing discussion it is apparent that considerable modification of the features of this invention are possible, and, while the devices shown and described and the forms of apparatus 15 for the operation thereof, constitute preferred embodiments of the invention, it is to be understood that the invention is not limited to these precise devices and forms of apparatus and that changes may be made therein without departing 20 from the scope of the invention which is defined in the appended claims.

What is claimed is:

1. A coaxial transmission line filter, for suppressing energy of one frequency and transmitting energy of another frequency, comprising an outer conductive member and an inner conductive member, said inner conductive member comprising a plurality of quarter wave length discontinuities each being of an odd number quarter wave lengths long at the frequency of the energy to be suppressed, and an impedance matching section connecting said discontinuities in series operative to match the impedance of the filter section to the line at the frequency of the energy to be transmitted, said impedance matching section comprising a diametrically enlarged odd quarter wave length portion at the frequency of the energy to be suppressed formed in said inner conductor in series relation with 35 said discontinuities.

2. A coaxial transmission line filter for suppressing energy of one frequency and transmitting energy of another frequency, comprising an outer conductor and an inner conductor, said inner conductor being provided with a plurality of odd quarter wave reentrant sections at the frequency of the energy to be suppressed formed in series therein and an impedance matching section connecting said reentrant sections in series operative to match the impedance of the filter section to the line at the frequency of the energy to be transmitted, said impedance matching section comprising a diametrically enlarged odd quarter wave length portion at the frequency of the energy to be suppressed formed in said inner conductor in series relation with said discontinuities.

3. A broad banded filter, for suppressing energy of one frequency and transmitting energy of another frequency, comprising; a coaxial transmission line having an outer conductor and an inner conductor, said inner conductor comprising at least a pair of spaced reentrant discontinuities therein each having a length of a quarter wave at the frequency of the energy to be suppressed and a conductive member bearing a raised central section having a length of approximately a quarter wave of the energy to be suppressed centrally positioned in said inner conductor between said reentrant discontinuities, said reentrant discontinuities forming two parallel resonant high impedance paths at the frequency of energy to be suppressed serially interposed in said inner conductor, said raised central section forming a shunt capacitance at the fre-

quency of energy to be suppressed, said raised central section further forming with said outer conductor a section of impedance converting transmission line, whereby impedance introduced by the first reentrant discontinuity at the frequency of energy of which transmission is desired, is cancelled by the impedance introduced by the second reentrant discontinuity at frequency of transmission.

4. In a broad banded filter as defined in claim 3, an annular cylinder of insulating material placed around the raised central portion of said conductive member for positioning said member in the outer conductor of the coaxial transmission line.

5. A coaxial transmission line filter for suppressing energy of one frequency and transmitting energy of another frequency comprising an outer conductive member and an inner conductive member, said inner conductive member comprising a plurality of tandemly connected line sections each having a length approximately a quarter wave length of the frequency of the energy to be suppressed, one of said sections further forming with said outer conductor a section of impedance converting transmission line for matching the impedance of the filter section to the line at the frequency of energy to be transmitted.

6. A broad band coaxial transmission line filter for supressing energy of one frequency and transmitting energy of another frequency, comprising; an outer conductor, an inner conductive member, said inner conductive member having an interruption therein with the ends of said interruption spaced apart a distance somewhat larger than a quarter of a wave length of the frequency of energy to be suppressed, a second conductive member having a diameter smaller than said inner conductor, coaxially and conductively connecting the ends of said interruption of said inner conductive member, a first conductive cylinder, in length less than said second

5 conductive member and having a first and second end, concentrically placed around said second conductive member and conductively attached at a first end of said interrupted inner conductive member and separated from the second end of said interruption of said inner conductive member, said first conductive cylinder forming with said second conductive member a first parallel resonant high impedance path at the frequency of energy to be suppressed, a second cylindrical conductive member concentrically placed around said first conductive cylinder and having a length less than said first conductive cylinder, conductively connected to said first conductive cylinder at the second end thereof, said second cylindrical conductive member forming with said first conductive cylinder a second parallel resonant high impedance path in series connection with said first parallel resonant high impedance path at the frequency of energy to be suppressed, said second cylindrical conductive member further forming with said outer conductor an impedance matching section operative to match the impedance of the filter section to the line at the frequency of the energy to be transmitted, and an annular cylinder of insulated material placed around said second cylinder for positioning said cylinder within the outer conductor of the coaxial transmission line.
